FLUID CHECK

Sterling O. Stageberg, Red Wing, Minn.

Application October 19, 1936, Serial No. 106,359

18 Claims. (Cl. 16—51)

My invention relates to fluid checks and has for an object to provide a fluid check which is exceedingly simple in construction.

Another object of the invention resides in providing a fluid check which is practical and efficient in operation.

An object of the invention resides in providing a check which can be readily manufactured and sold at a low cost.

10 A still further object of the invention resides in constructing the check so that the same may be mortised into the edge of a door.

An object of the invention resides in providing a check in which a leaf spring is employed which 15 performs the dual purpose of affording power for moving the object with which it is connected and also forms the expandible chamber by means of which timed operation of the device is procured.

20 A still further object of the invention resides in the specific construction and arrangement of parts by means of which the expandible chamber is formed.

25 Another object of the invention resides in the specific construction and arrangement of parts by means of which the control of fluid from and to the expandible chamber is procured.

An object of the invention resides in forming the fluid control means by procuring resilient 30 contact of the leaf spring with one of the convolutions thereof or with the wall of the case in which the spring is installed or by engagement with a movable plate.

35 A feature of the invention resides in providing a cylindrical or other longitudinally extending compartment in the case and in mounting the rotatable member to which the leaf spring is attached eccentrically within said compartment.

40 Another object of the invention resides in constructing the fluid chamber with a movable end plate adapted to engage the edge of the spring to form a tight joint therebetween.

45 A still further object of the invention resides in constructing the device so that said movable end plate is urged into engagement with the spring through the pressure created in the device.

A specific object of the invention resides in utilizing said movable end plate as a valve.

50 Other objects of the invention reside in the novel combination and arrangement of parts and in the details of construction hereinafter illustrated and/or described.

In the drawings:

55 Fig. 1 is a perspective view of a portion of a

door and frame illustrating the application of an embodiment of my invention thereto.

Fig. 2 is an elevational sectional view taken on line 2—2 of Fig. 1.

Fig. 3 is an inverted plan sectional view taken on line 3—3 of Fig. 2 and drawn to a smaller scale.

Fig. 4 is a fragmentary detail sectional view taken on line 4—4 of Fig. 3.

Fig. 5 is a view similar to Fig. 1 of a modification of the invention.

Fig. 6 is an elevational sectional view taken on line 6—6 of Fig. 5.

Fig. 7 is an inverted plan sectional view taken on line 7—7 of Fig. 6.

Fig. 8 is a view similar to Fig. 7 of a portion of the structure illustrated therein and showing the parts in altered position.

For the purpose of illustrating my invention, I have shown in Fig. 1 a door 10 mounted within 20 a door frame 11 having a casing 12 extending about the same and provided with a header 20. Door 10 is hung on the frame 11 by means of hinges 19. This construction has been shown merely for the purpose of illustrating the manner of attaching the invention thereto and since the specific construction of the door and frame forms no feature of the invention, the details thereof have not been disclosed in this application.

30 The check proper illustrated in Fig. 1 comprises a case 13 preferably constructed of sheet metal, which is provided with a cylindrical wall 14 and a bottom 15, both stamped out of the same sheet of material. The wall 14 is enlarged at its upper end as indicated at 16 to form a shoulder 17, the purpose of which will be presently described in detail. The case 13 is closed by means of a cap 18 which is also constructed from sheet metal and which is constructed with a cylindrical wall 21 adapted to fit into the portion 16 of case 13. This cap is constructed with a top 22 similar to the bottom 15 of the case 13. For securing the cap 18 in position a number of machine screws 23 are employed, which pass 40 through the portion 16 of case 13 and are threaded into the cylindrical wall 21 of the cap 18.

45 The case 13 is mounted on the door 10 by means of a bracket 24, best shown in Fig. 1. This bracket is constructed from a strip of 50 sheet metal and is provided with a cylindrical portion 25 enveloping the cylindrical portion 14 of case 13 and with two legs 26 extending outwardly therefrom. Two feet 27 formed on the said legs rest against the portion of the door 55

10 on which the check is to be mounted. A bolt 28 passes jointly through the two legs 26 and serves to clamp the cylindrical portion 25 firmly about the case 13 and to hold the bracket 5 24 securely attached to said case. Screws 31 extend through the feet 26 and are screwed into the door 10, whereby the check is properly mounted upon the door.

Within the interior of the case 13 is disposed a 10 partition 32 which is of a thickness considerably greater than that of the walls of the case 13 and the cap 18 and which fits snugly within the portion 16 of the case. This partition rests upon the shoulder 17 formed at the juncture of the 15 portion 16 of case 13 with the wall 14 thereof. Partition 32 is held against this shoulder by means of the extreme edge 33 of the cylindrical portion 21 of cap 18 which butts against the upper surface of said partition as clearly shown 20 in Fig. 2. Partition 32 divides the interior of the case 13 into two compartments indicated by the reference numerals 34 and 35, the former being above the partition and the latter below it.

Mounted within the case 13 is a shaft 36 25 which is journaled for rotation with respect to said spindle in a bearing 37. Bearing 37 is reduced at its ends as indicated at 42 and 43, which parts fit into holes 44 and 45 formed in the top 22 of cap 18 and in the partition 32 respectively. 30 The shoulders 46 and 47 formed at the reduced portions 42 and 43 of the bearing 37 hold the said bearing in proper position and also assist in maintaining the partition 32 seated upon the shoulder 17 of case 13. The shaft 36 is constructed with a portion 48 which is journaled in the bearing 37 and is constructed with another portion 51 reduced in diameter and which extends into the compartment 35 of case 13. The extreme end 52 of this shaft is further reduced 35 in diameter and is journaled in a bearing 53 screwed into the bottom 15 of case 13.

The portion 52 of shaft 48 is fluted or constructed with splines as shown in Fig. 3 and has attached to it a cylindrical head 54 of dimensions somewhat less than the height of the compartment 35 and substantially equal to the distance between the end 55 of bearing 53 and the end 56 of bearing 37. This head seats against the under surface 57 of partition 32. 45 Within the interior of compartment 37 is disposed a spiraled leaf spring 58 which is attached at one end 61 to the cylindrical wall 14 of case 13 by means of bolts 62. The other end of this leaf spring is constructed with a loop 63 which is lodged within a cylindrical socket 64 in the periphery of the head 54. This socket is constructed by drilling or otherwise machining the head and is of a circular extent greater than a semi-circle so that when the loop 63 is lodged 50 within the same, said loop becomes firmly mounted within said socket and cannot be displaced therefrom, excepting by endwise movement of the said loop out of said socket. The spring 58 consists of three convolutions 65, 66 and 67 which are successively larger in diameter. The shaft 48 is so positioned with respect to the wall 14 of the case 13 that said convolutions where they pass between the head 54 and said wall fit snugly therebetween and prevent leakage 60 of fluid through the lines of contact between said convolutions and the head and case of the device. By means of these convolutions a number of chambers 71, 72, 73 and 74 are formed between the head 54, the case 13 and the various convolu-

tions, which chambers function in a manner to be presently described in detail.

For closing the lower end of the chambers 71, 72, 73 and 74 an end plate 75 is employed which is disposed within the lowermost portion of the 5 case 13. The upper surface 70 of this end plate seats against the lower end surface 76 of the head 54 and also against the lower edges 77 of the spring 58. The upper edges 78 of said spring engage the under surface 57 of the partition 32. 10 Both the head 54 and the spring 58 are accurately ground to height so that a close fit is formed between the same and the partition 32 and plate 75, to make the chambers 71, 72 and 73 leak proof with respect to the chamber 74 when the 15 parts are urged together. Plate 75 fits loosely within the case 13 and is constructed with a hole 81 loosely encircling the bearing 53. A crinkle spring 82 disposed between the bottom 15 of case 13 and said plate urges the parts into engagement. By means of the plate 75 another chamber 83 is formed below said plate which is always in communication with the chamber 74 and forms a part thereof.

The chambers 71 and 72 communicate with 25 the compartment 34 by means of two holes 84 and 85 which are drilled directly through the partition 32. These holes are also in communication with one another through a hole 86. Chamber 73 is in communication with the hole 30 86 through another hole 87. A screw 88 threaded in the partition 32 is formed with a conical point 91 adapted to close the hole 87 and also to enter the hole 85. By means of this screw the rate of entry of fluid into chambers 72 and 35 73 may be controlled.

The chamber 74 is connected to the compartment 34 by means of holes 92, 93 and 94 which are arranged as shown in detail in Fig. 4. A screw 95 similar to screw 88 controls the rate of 40 flow through these various holes.

The shaft 36 is formed with a protruding portion 96 which is fluted or splined and is similar to the portion 51 and which has attached to it an arm 97. The portion 96 is reduced in diameter 45 with respect to the major portion of said shaft to form a shoulder 98 against which said arm is seated. The extreme end 101 of said shaft is threaded to receive a nut 102 which clamps the arm 97 against the shoulder 98 and 50 holds the arm firmly secured to shaft 36. Arm 97 is pivoted by means of a bolt 103 to a link 104 which in turn is pivoted by means of a bolt 105 to a bracket 106. Bracket 106 is attached to the header 12 of casing 11 by means of screws 55 107 and said bracket is mounted on said casing in approximately the location shown in Fig. 1. When the door 10 is opened and closed, arm 97 is rotated in a manner to be presently described in detail and the spring 58 tensioned and 60 released to effect timed movement of the door. The interior of the case 13 is filled with a suitable oil which is inserted into the same through an oil hole 108 closed by means of a cap 109.

The operation of the device shown in Figs. 1 65 to 4 is as follows: When the door 10 is moved into opening position and swung about the hinges 19, arm 97 is given a clockwise movement when viewed from below. Spring 58 is normally straight and when coiled as shown in Fig. 3, exerts a pressure tending to procure counter-clockwise movement of the shaft 48 when viewed from beneath the device. Clockwise movement of the head 54 causes further tensioning of the spring 70 58 which closes up the chambers 71, 72 and 75

13 and which increases the size of the chamber 74. Any oil which may be contained in the chambers 71, 72 and 73 is forced out between the edges 77 of the spring 58 and the plate 5 75 which yields downwardly through the action of the spring 82. This oil flows along the plate 75 and quickly enters the chamber 74. When the door 10 has been opened the proper amount and the said door is released, spring 57 immediately tends to assume its normal position and produce counter-clockwise movement of the shaft 48 and head 54. Pressure is now created 10 in chamber 74 and suction in chambers 71, 72 and 73. The oil contained within chamber 74 is forced through the holes 92, 93 and 94 and into compartment 34 and the chambers 71, 72 and 73 are filled with oil from said compartments which travel through the holes 84, 85, 86 and 87. Flow through these various holes is controlled 15 by the two screws 88 and 95. It may become desirable to have the door closed more rapidly at the outset than when approaching closing position. This can be accomplished by means of the screw 88 and in such case holes 20 84 and 85 are left wide open and the hole 87 partly covered. In this manner the spring 57 forces the door into closing position and the various ports control the movement of said spring 58 to procure timed closing of the door. 25

30 It will be noted that when checking is being procured that chambers 71, 72 and 73 are under suction and that chamber 74 is under pressure. The suction created in these first named chambers tends to draw the partition 32 and plate 75 toward one another and effect a seal between the surfaces 57 and 70 and the edges 77 and 78 of the spring 58 and also between the ends of the head 54 and the surfaces 57 and 70. Thus leakage is prevented into these chambers excepting 35 through the controlled ports provided therefor. The pressure in chamber 74 is communicated to the chamber 83 and the pressure in this chamber merely serves to urge the plate 75 into engagement with the spring as previously described. 40

45 The bearing 53 being screwed tight to the bottom 15 it becomes impossible for oil to leak out of the case. If leakage of oil should occur between the partition 32 and the portion 16 of said case 13 such oil would merely flow into the compartment 34 which serves as a reservoir for oil. A 50 lesser opening of the ports between chamber 74 and compartment 34 controlled by screw 95 would then be required so that any variation in the construction of these parts would not alter the operation of the invention. Compartment 34 serves merely as a reservoir for the surplus oil and is at no time under pressure. There is, therefore, no danger of leakage of oil out of the check through any portion of the same and once 55 the check has been filled with oil, the same continues to operate indefinitely.

60 In Fig. 5 I have shown a modification of the invention which is adapted to be mortised into the upper rail 29 of the door 10 instead of being attached to the exterior of the door. This device consists of a case indicated in its entirety by the reference numeral 111 which is stamped from a single sheet of material to provide a bottom 112, spaced parallel side walls 113 and 114, curved side walls 115 and 116 connected therewith and a flange 117 extending about all of said side walls. By means of this construction a chamber 110 is formed within the case. The case 111 is closed by means of a closure 118 which is constructed 65 as a casting and is provided with upper and lower 70 walls 121 and 122 to provide a chamber 123 between the same. The two walls 121 and 122 are connected together at the marginal portions of the same as indicated at 124 to close said walls at their edges. The closure 118 extends outwardly beyond the portion 124 of the structure to form a flange indicated by the reference numeral 125. The case 111 is secured to the closure 118 by means of screws 126 which pass through the flange 117 of said case and are threaded into the flange 125 of closure 118. The entire structure is attached to the rail 29 of door 10 by means of wood screws 128 which extend through the flange 125 and are screwed into the rail proper. The case 111 is set into a mortise 129 in rail 29 while the flange 125 is received within a recess 131 in the upper portion of the rail, making the housed portion of the device flush with the upper edge of the door. 15

20 In the bottom 112 of case 111 is formed a depressed boss 132 which is constructed with a socket 133 serving as a bearing for the lower end 134 of a shaft 135. The upper end 136 of this shaft is journaled in a bore 137 formed in a boss 138 connecting the two walls 121 and 122 of closure 118. The portions 136 and 134 of shaft 135 are cylindrical to journal said shaft for rotation while the intermediate portion 120 of said shaft is ovular as best shown in Figs. 7 and 8 for a purpose to be presently described in detail. 25

30 The extreme end of the portion 136 of shaft 135 is fluted as designated at 139 to receive an arm 141 which is held in place upon said shaft by means of a machine screw 142. This arm is pivoted at 143 to another arm 144 which in turn is pivoted at 145 to a bracket 146 secured to the header 20 of casing 12 of the door frame 11. As the door is opened, shaft 135 swings from the position shown in Fig. 7 to that shown in Fig. 8. 35

40 Attached to the wall 122 of closure 118 are two depending brackets 147 and 148 which are constructed with outwardly extending flanges 151 and 152. These brackets are attached to said wall by means of screws 153 which pass through said flanges and are threaded into the wall 122. 45 The brackets 147 and 148 have bosses 155 and 156 formed thereon which project outwardly therefrom and which are disposed approximately midway between the upper and lower walls of the case 111. 50

55 Secured to the shaft 135 are two leaf springs 161 and 162, the ends 163 and 164 of which are clamped between the ovular portion 120 of the shaft 135 and two segmental shaped clamp bars 165 and 166 secured in clamping relation by means of screws 167 which pass through one of said bars and the shaft 135 and are threaded into the other bar. The composite structure when assembled is substantially cylindrical to facilitate coiling of the springs thereon. The leaf spring 161 is constructed with two reaches 171 and 172 which lie along the walls 113 and 114 of the case 111 and which are connected together by means of a looped portion 173. The spring 162 is similarly constructed with spaced parallel reaches 175 and 176 which lie along the walls 113 and 114 of case 111 and with a looped portion 177 connecting the same together. The reach 172 of spring 161 is attached to a flange 178 formed on the bracket 147 and extends outwardly beyond said bracket overlying the reach 175 of spring 162. 60 In a similar manner the reach 176 of spring 162 is secured to a similar flange 179 on the bracket 148 and extends outwardly beyond said bracket and overlies the reach 171 of spring 161. 65

70

75

Within the looped portion 171 of spring 161 is disposed a bearing 181 which is constructed in the form of a spool, being provided with a core 182 riveted to two cylindrical heads 183 and 184. These heads engage the inner surface of the looped portion 173 of the spring 161 and when pressure is applied to the core 182 thereof, urge the looped portion 173 towards the wall 115 of the case, causing a rotation of shaft 135. The bearing 181 is urged in the direction specified by means of a coil spring 185 which is seated at one end against the boss 155 and at its other end against a shoulder 186 formed on a shoe 187 having an arcuate socket 188 engaging the core 182 of the said bearing 181. This shoe is constructed with a shank 189 which is received within the spring 185 and which holds the shoe 187 in proper position. It will readily be comprehended that spring 185 tends to force the bearing 181 toward the end wall 115 of case 111, thereby lengthening the reaches 171 and 172 of spring 166 and turning the shaft 135 in a counter-clockwise direction.

In the loop 177 of spring 161 is a bearing 191 identical with the bearing 181 which is urged toward the end 116 of case 111 by means of a compression coil spring 192. This spring is seated at one end against the boss 156 on bracket 148 and at its other end against a shoe 193 identical with the shoe 187. The two springs 185 and 192 operate jointly to procure torque of the shaft 135 in the same direction, whereby rotation of said shaft is effected as the springs expand.

35 The two springs 161 and 162, as stated, are leaf springs and are of a height less than the distance between the lowermost surface 194 of wall 122 of closure 118 and the bottom 112. Within the chamber 110 is provided a follower plate 195 which fits freely within the interior of the case 111 and is disposed above the bottom 112 thereof. This plate is drilled at 196 to fit over the portion 134 of shaft 135 and bears against the lowermost edges of the leaf springs 161 and 162, being urged into engagement therewith by means of a compression coil spring 198 extending between said plate and the bottom 112 of case 111. The lengths of the intermediate portion 120 of the shaft 135 and the clamp bars 165 and 166 are exactly of the same length as the width of the springs 161 and 162 so that the plate 195 may be urged snugly against the ends of the springs and parts to form fluid tight connections therebetween. By means of the construction described, the chamber 110 is divided into two compartments 197 and 198 within the reaches of the springs 161 and 162, two other compartments 201 and 202 upon the exterior of said springs and another compartment 203 beneath the plate 195 and between it and the bottom 112 of case 111. These various compartments communicate with one another in the following manner:

Drilled in the portion 124 of closure 118 are two holes 204 and 205 which communicate with the compartments 201 and 202 respectively. Adjusting screws 206 and 207 threaded in the closure 118 control the rate of flow from the chamber 123 to the compartments 201 and 202. In a similar manner, holes 208 and 209 are drilled in the walls 122 of closure 118 which communicate with the compartments 197 and 198 and with the chamber 123. The rate of flow through these passageways is also regulated by means of adjusting screws 211 and 212 threaded into the wall

121 of said closure. The entire interior of the chamber 110 and the chamber 123 is filled with a suitable liquid, such as lubricating oil, glycerine, or any other similar liquid, suitable for use for the purpose. The chamber 123 is filled through 5 an opening 213 in the wall 121 of closure 118 which is closed by a cap 214. The chamber 110 is similarly filled with oil prior to the application of the same to the closure 118.

The operation of the form of the invention 10 shown in Figs. 5, 6, 7 and 8, is as follows: When the door 10 is being opened, the shaft 35 is rotated in a clockwise direction as viewed in Figs. 7 and 8. This causes the reach 171 of spring 161 and the reach 175 of spring 162 to be wrapped 15 about the shaft 135 and the two clamp bars 165 and 166 as indicated at 168 and 174. Such action shortens such portions of the springs 161 and 162, thus drawing the two loops 173 and 177 toward one another. Such movement compresses the two 20 springs 185 and 192. The position of the parts when the door is open, is shown in Fig. 8. During movement of the parts from the positions shown in Fig. 7, to those shown in Fig. 8, the oil within the compartments 197 and 198 is discharged 25 therefrom. This is accomplished as follows: As soon as these compartments become smaller in size, pressure is created within the same which forces the plate 195 downwardly, permitting the oil to escape between the edges of the springs 30 161 and 162 and the upper surface of said plate, and also between the overlapping portions of the ends of said springs and the parts 174 and 168 thereof, and into the compartments 201 and 202. The escape of the oil in this manner is without 35 resistance so that the movement of the door from closing to partly open position is accomplished without appreciably greater effort than required to compress springs 185 and 192. When the door is released the linkage consisting of arms 141 40 and 144 tends to rotate the shaft 135 in a counter-clockwise direction as viewed in Figs. 7 and 8. This action is, however, limited by the two leaf springs 161 and 162 which retard the rotation 45 of the shaft in the following manner. The pressure in this instance being released from the springs 161 and 162, the springs 185 and 192 tending to urge the bearings 181 and 191 toward the walls 115 and 116 of case 111. This causes a reduction of pressure in the two compartments 50 197 and 198 and pressure in the compartments 201, 202 and 203. Such pressure forces the plate 195 against the lowermost edges of the springs 161 and 162 and prevents leakage of oil past the same. The tendency for the oil to flow is through 55 the passageways 204 and 205 into the chamber 123 and from this chamber through the passageways 208 and 209 into the compartments 197 and 198. Such flow of oil is regulated by the adjusting screws 206, 207, 211 and 212. By means of 60 the adjustment of these screws any timing of the operation of the device can be procured. When the looped portions 173 and 177 of the springs 161 and 162 pass the holes 208 and 209, as shown in Fig. 8, movement of the parts is extremely 65 slow. As soon as the loops 173 and 177 reach the openings 208 and 209, the timing is controlled and the device operates in the desired manner.

Although I have shown but a single pair of openings 208 and 209 it can readily be comprehended that other additional openings of similar nature may be employed, so that the acceleration of the doors into closing position may be modified to suit the particular requirements.

The advantages of my invention are manifest. 75

Timed operation can be procured without the use of pistons or tightly fitting movable parts. The structure forming part of the expandible chamber also forms the valve, thereby eliminating numerous parts. Wear of the parts of the invention will not greatly reduce the effectiveness of the device. The device can be constructed at a nominal cost. Regulation of the operation of the invention can be easily procured.

10 Changes in the specific form of my invention, as herein disclosed, may be made within the scope of what is claimed without departing from the spirit of my invention.

Having described my invention, what I claim as new and desire to protect by Letters Patent is:

1. In combination, a case providing a compartment having spaced parallel walls, a rotatable member within said compartment rotatable about an axis extending at right angles to said walls, 20 leaf spring means within said compartment attached to means fixed relative to said case and to said rotatable member and extending from one wall to the other, said leaf spring means having overlapping parts contacting with one another and dividing said compartment into two 25 chambers adapted to vary in volume upon rotation of said rotatable member, said overlapping parts being urged into contact through the resiliency of said spring means and forming a check 30 valve between said chambers.

2. In combination, means forming a compartment having spaced parallel end walls and a cylindrical wall between said end walls, a rotatable member within said compartment rotatable 35 about an axis at right angles to said end walls and disposed eccentrically with respect to said cylindrical wall, a spiral leaf spring within said compartment attached at one end to said cylindrical wall and at its other end to said rotatable 40 member, means including a part of said leaf spring for dividing said compartment into two chambers, said means being disposed at the portion of the cylindrical wall of the case nearest the axis of said rotatable member.

45 3. In combination, means forming a compartment having spaced parallel end walls and a cylindrical wall between said end walls, a rotatable member within said compartment rotatable about an axis at right angles to said end wall and disposed eccentrically with respect to said cylindrical wall, a spiral leaf spring within said compartment attached at one end to said case and at its other end to said rotatable member, said leaf spring contacting with the portion of the cylindrical wall nearest the axis of said rotary member and being spaced from said wall on the opposite sides of the contacting portion thereof to form two chambers within said compartment, and fluid flow control between said chambers.

60 4. In combination, means forming a compartment having spaced parallel end walls and a cylindrical wall between said end walls, a cylindrical head within said compartment rotatable about an axis extending at right angles to said end walls and disposed eccentrically with respect to said cylindrical wall, a spiral leaf spring within said compartment attached at one end to said cylindrical wall and at its other end to said head, said spring extending between said wall and head 65 and at one locality filling up the space between said wall and head, said leaf spring forming in conjunction with said cylindrical wall and head two chambers of variable capacity and fluid flow control means acting between said chambers.

70 5. In combination, means forming a compart-

ment having spaced parallel end walls, and a longitudinal wall between said end walls, a rotatable member within said compartment rotatable about an axis extending at right angles to said end walls and disposed eccentrically with respect to said longitudinal wall to form an enlarged space between said circumferential wall and said member on one side of said member, a looped leaf spring attached to said member and to said longitudinal wall and engaging said end walls, 10 said spring extending into said enlarged space, and forming therein two chambers adapted to vary in volume upon rotation of said rotatable member, and fluid flow control means acting between said chambers.

15 6. In combination, means forming a compartment having spaced parallel end walls, and a circumferential wall between said end walls, a rotatable member within said compartment rotatable about an axis extending at right angles to said end walls and disposed eccentrically with respect to said circumferential wall to form an enlarged space between said circumferential wall and said member on one side of said member, a looped leaf spring attached to said member and to said 20 circumferential wall and engaging said end walls, said spring extending into said enlarged space, and forming therein two chambers adapted to vary in volume upon rotation of said rotatable member, one of said chambers being crescent 25 shaped, and fluid flow control means acting between said chambers.

30 7. In combination, means forming a compartment having spaced parallel end walls, and a longitudinal wall between said end walls, a rotatable member within said compartment rotatable about an axis extending at right angles to said end walls, a leaf spring attached at one end to said member and at its other end to said wall, said spring having a plurality of convolutions, one 35 of the convolutions contacting with another of the convolutions at one locality and being spaced from said convolutions at another locality to form a chamber between said convolutions, and another chamber on the other side of one of 40 said convolutions, and fluid flow control means between said chambers.

45 8. In combination, means forming a compartment having spaced parallel end walls and a cylindrical wall between said end walls, a cylindrical head within said compartment rotatable about an axis extending at right angles to said end walls and disposed eccentrically with respect to said cylindrical wall, a spiral leaf spring within said compartment attached at one end to said cylindrical wall and at its other end to said head, said spring having a convolution encircling another of said convolutions and engaging said convolution at spaced localities to form in conjunction therewith a crescent shaped chamber 50 between said convolutions and another chamber upon the exterior of one of said convolutions, said convolutions resiliently engaging one another to form a valve between said chambers.

55 9. In combination, means forming a compartment having spaced parallel end walls, and a longitudinal wall between said end walls, a rotatable member within said compartment rotatable about an axis extending at right angles to said end walls, a leaf spring attached at one end to said member and at its other end to said wall at one locality, and engaging said wall at another locality, said spring being spaced from said wall intermediate the locality of attachment and engagement to form a chamber therebetween, and 60

a chamber on the other side of said spring, and fluid flow control means between said chambers.

10. In combination, means forming a compartment having spaced parallel end walls, and a longitudinal wall between said end walls, a rotatable member within said compartment rotatable about an axis extending at right angles to said end walls, a leaf spring attached at one end to said member and at its other end to said wall at one locality, and engaging said wall at another locality, said spring being spaced from said wall intermediate the locality of attachment and engagement to form a chamber therebetween, and a chamber on the other side of said spring, said 15 spring resiliently engaging said wall to form a valve between said chambers.

11. In combination, means forming a compartment having spaced parallel end walls and a cylindrical wall between said end walls, a rotatable member within said compartment rotatable about an axis at right angles to said end wall, a spiral leaf spring within said compartment encircling said member and attached at one end to said member and at its other end to said wall, 25 said spring being spaced from said wall intermediate the locality of attachment and engagement to form a crescent shaped chamber therebetween and a chamber on the other side of said spring, and fluid control means between said 30 chambers.

12. In combination, a case having a circumscribing wall structure and open at the top, a cap for closing the top of said case, a partition within the case extending across the circumscribing wall 35 structure and spaced from the cap to form a fluid reservoir therebetween, planiform means extending across the circumscribing wall structure and spaced from said partition and forming in conjunction with said circumscribing wall structure and partition a compartment within the case, a rotatable member within the case, a leaf spring within the case attached at one end to said member and at its other end to means fixed relative to the circumscribing wall structure and 40 extending between said partition and said planiform means, said spring forming within said compartment two chambers, and flow control means between said chambers, said fluid flow control means including said reservoir.

13. In combination, a case having a circumscribing wall structure and spaced end walls, a rotatable member within said case, a movable plate within said case spaced from both of said end walls and parallel to and movable toward and 45 from one of them and forming a compartment between itself and the other wall, a leaf spring disposed between said plate and parallel wall, said spring being attached to said rotatable member and to means fixed relative to said case, 50 and operating to rotate said rotatable member, said spring forming two variable volume chambers between said plate and parallel wall containing a fluid, one of said chambers being under greater pressure than the other when the spring 55 is rotating said rotatable member, said chamber being in communication with said compartment to create a pressure therein for urging said plate toward said parallel wall and against said spring, said plate moving away from said spring when the

action of the spring is reversed to conduct fluid freely from one chamber to the other, and means for controlling the flow of fluid between said chambers when the spring is rotating said rotatable member.

14. In combination, a case having a circumscribing wall structure and spaced end walls, a rotatable member within said case, a movable plate within said case spaced from both of said end walls and parallel to and movable toward 10 and from one of them and forming a compartment between itself and the other wall, a leaf spring disposed between said plate and parallel wall, said spring being attached to said rotatable member and to means fixed relative to said case 15 and forming two variable volume chambers, one of said chambers being in communication with said compartment, and means for controlling the flow of fluid from one of said chambers to the other.

15. In combination, an elongated case, a rotatable member disposed near the center of the case, a pair of looped leaf springs within said case on opposite sides of said member, said springs being secured to said member and to means fixed 25 relative to the case, said springs forming pairs of chambers containing a fluid, and means for controlling the flow of fluid from certain of said chambers to others of said chambers.

16. In combination, an elongated case, a rotatable member disposed within said case, a looped leaf spring within said case secured at one end to said member and at its other end to means fixed relative to the case, said spring forming a pair of chambers containing fluid, and means 35 for controlling the flow of fluid from one chamber to the other upon rotation of said rotatable member.

17. In combination, an elongated case, a rotatable member disposed within said case, a looped leaf spring within said case secured at one end to said member and at its other end to an abutment positioned in proximity to said rotatable member, means disposed within the loop of said spring and a resilient member extending between 45 said abutment, a bearing for urging said means away from said abutment and procuring rotation of said rotatable member.

18. In combination, an elongated case having side walls and top and bottom walls, a rotatable member disposed near the center of the case and rotating about an axis at right angles to said top wall, a pair of looped leaf springs within said case having their upper edges engaging the top wall, a plate within said case engaging the lowermost edges of said leaf springs, abutments in said case disposed in proximity to said rotatable member, said leaf springs being attached at one end to said rotatable member and at their other ends to said abutments, said springs being formed with loops intermediate their ends, means within said loops and resilient means acting between said abutments, a bearing for urging said means away from said abutments and procuring rotation of said member, said leaf springs forming pairs of chambers having a fluid therein, and means for controlling the flow of fluid from certain of said chambers to others of said chambers.

STERLING O. STAGEBERG.
